UNITED STATES PATENT OFFICE.

CHARLES E. TORRANCE, OF SPRINGFIELD, MASSACHUSETTS.

PAPER-CALENDERING MACHINE.

SPECIFICATION forming part of Letters Patent No. 394,522, dated December 11, 1888.

Application filed March 28, 1887. Serial No. 232,708. (No model.)

To all whom it may concern:

Be it known that I, CHARLES E. TORRANCE, a citizen of the United States, residing at Holyoke, in the county of Hampden and State of 5 Massachusetts, have invented new and useful Improvements in Paper-Calendering Machines, of which the following is a specification.

This invention relates to paper-calendering machines, the object being to improve the construction of the paper-guiding devices thereof, the means by which they are attached to the machine and hung opposite the rolls, and means for preventing the introduction of 10 more than one sheet of paper into the calender at a time; and the invention consists in the peculiar construction and combinations of the above-referred-to parts of the calender, all as hereinafter fully described, and pointed 15 out in the claims.

In the drawings forming part of this specification, Figure 1 is an elevation of the inner side of one of the upright end frames of a paper-calendering machine, having applied thereto paper-guiding devices embodying my 20 improvements, said figure showing the outlines of the calender-rolls in dotted lines, the journal at one end thereof in section, and the journal-boxes in end elevation. Figs. 2 to 8, 25 inclusive, illustrate in perspective views (excepting Fig. 5, which is a transverse section) details of constructions, hereinafter fully described. Fig. 9 is a perspective view of the upper part of the calendering-machine, showing the sheet-guard devices thereon. Fig. 10 30 is a plan view of one of the sheet-guiding blades of the calender and its supporting-saddle. Fig. 11 is a similar view to Fig. 9, showing one of the calendering-rolls in sectional 35 elevation and a side elevation of one of said sheet-guard devices suspended thereover.

In the drawings, 3 indicates one of the end uprights of the machine-frame, and is shown in side elevation in Fig. 1 and in transverse 40 section in Fig. 5. The said upright has the usual vertical opening therein, in which are placed the journal-boxes 4, in which the journals of the calender-rolls are supported, 5 being the usual pressure-screw, (the upper end 45 being broken off,) having a bearing against the upper box of the machine for forcing the

rolls against each other in the usual way. On the inner side of said frame-upright 3 are secured two upright strips, 6, one on each side of the rolls of the machine, said strips having a longitudinal groove therein, made by turning inward the opposite edges thereof, whereby said groove is given a T shape in cross-section, as shown in Fig. 5, whereby said strips are adapted to hold a bolt or bolts by 55 the head thereof, so that the bolt is sustained in substantially a horizontal position. Fig. 7 shows a portion of one of said grooved strips 6, and a bolt, 7, secured thereto adjustably by its head. The bolt 7, when simply hung by 60 its head in the groove in the strip 6, does not maintain a position at right angles to the face of the groove, unless the thickness of the head and the depth of the groove correspond, and in that case the head fits too tightly to permit 65 of moving the bolt up and down with freedom, and therefore to make said means of attaching the bolt 7 to the calender-frame available, and still permit the bolt to be moved with sufficient freedom in the strip, and to 70 cause the bolt to be maintained at a position at right angles to the face of the strip 6, as shown in Fig. 7, a spring, 8, is suitably attached to the head of the bolt, and has its ends bearing upon the side of the strip at the base of 75 its groove, whereby the bolt is forced endwise outwardly, causing the inner side of its head to come to a bearing under the opposite in-turned edges of said strip, as shown.

By means of the above described connection 80 of the bolt 7 with the said strip 6 the bolt retains its position when certain fixtures, hereinafter described, are disconnected therefrom for adjustment, and thereby much time is saved when the fixtures are reattached to the bolt 85 from the fact that the bolt itself does not require any readjustment.

On the side of the upright 3 near its lower end is bolted a roller-support, 9, a portion of 90 which is shown in perspective in Fig. 8. The said support 9 is provided with a T-shaped groove, 10, of substantially the form of that in said strip 6, in which is shown the head end of a bolt, 12, which is connected in said strip 10 in substantially the same manner as 95 said bolt 7 is connected to the strip 6, the said bolt 12 serving to secure a fixture-support, 13,

to said horizontal support 9, the latter having thereon a slotted upright, 14, to receive the boxes in which two sheet-delivery rolls, 15, run.

- 5 The tape-rolls 17 and the sheet-guiding blade-rolls 16 are supported in peculiarly-constructed bearings in one end of the arms 18 and 19, in order that said rolls may be easily removed from said arms for any required purpose without removing the supporting-arms from the frame of the machine, or in the least disturbing their adjustment, for in machines of this class it is desirable that said arms when once adjusted to the requisite positions 15 to properly hold the rolls over which the tapes run and on which said blades are hung should not be disturbed if it can be avoided, for their adjustment to their proper positions requires much time and care. The said bearings in 20 the ends of the arms 18 and 19 consist of a metallic sleeve, 20, inserted in the end of each arm or in one arm of the two which support any one roller or rod, said sleeve being capable of endwise motion in said arms, whereby 25 it is withdrawn wholly or partially from the arm, as may be required, to leave the end of the roller-shaft which has a bearing within said sleeve quite free to be disengaged from said supporting-arm.
- 30 In Fig. 6 the sleeve 20 is shown in connection with the arm 19, and both this and the arm 18 are slotted longitudinally, as shown, from the sleeve-bearing therein toward the opposite end, and near said bearing is placed a 35 clamp-screw, 21, passing transversely through the arm and across said slot, whereby said sleeve 20 is clamped, and thereby secured in any desired position, or it is freed to permit it to be moved in the arm, as aforesaid.
- 40 In Fig. 3 one end of one of said rollers 17 is shown, and in dotted lines the shaft of said roller is indicated as entering the end of the sleeve 20, which adjoins said roller, the shaft of the roller in practice entering said sleeve 45 only far enough to give it a proper support, and not so far as to render it inconvenient to remove the roll when the sleeve is withdrawn from the end of the latter, as above described. The aforesaid slot in the arms 18 and 19 is 50 made wider near one end, as shown, so that the bolt 7 may pass through the arms, and a nut being screwed against the latter they are thereby secured to the strip 6 and to the upright-frame part 3 on the opposite sides of the 55 calender-rolls, as shown.

For the purpose of affording improved guides for the sheets of paper as they emerge from between the rolls of the calender, metallic blades 22 are provided, and are supported 60 on said rolls 16 by means of the below-described devices.

It is well known to those skilled in the art of calendering paper that it is inclined to adhere to the rolls as it passes between them, 65 owing to more or less electrical action caused by the compressing effect of the rolls upon the paper, whereby said sheets tend to adhere

thereto instead of properly following the usual guide-tapes, which are run in the ordinary way in conjunction with said rolls. Furthermore, when metal strips or fingers which bear rigidly against said rolls are employed to cause the paper to separate from the latter after passing therebetween said rolls become injured by having rings or grooves worn in 70 their surfaces, caused by a too forcible contact of metal pieces with the roll; and to obviate the above-named inconveniences in the paper-calendering process, and to provide greater conveniences in adjusting and manipulating the said devices, which cause the sheets to follow their proper course through the machine, is one of the principal objects of this invention. The said metallic blades are made of such width as may be desirable and 80 as adapts them to be placed in and supported by either one of the blade-saddles 23 and 24, Figs. 2, 4, and 10, and to each of the blades which are hung on the saddles 23 is attached a weight, 25, near the outer end of said blade, 90 which is adjustable longitudinally thereon, and is secured in any desired position by a suitable screw shown on certain of said weights. The inner ends of said blades are caused by the said weights attached thereto 95 to be held against the upper one of each pair of rolls, as shown, with such impact force as may be determined by said weight and the position of the saddle 23 on which the blade rests relative to the weight. A spring may 100 be used in place of said weight, if desired; but its action would be less satisfactory, because less uniform than the weight.

The saddle 23 consists of a metallic bearing-block, *a*, having a curved bearing-groove, 105 *c*, in its under side, which adapts said block to rest on said rolls or rods 16, and to have a free rocking motion thereon. Said block *a* has a screw, *e*, in one end, which passes through the slotted pending end of a tapering key, *b*, 110 whereby the latter is given an endwise motion in a groove, *d*, on the upper side of the saddle. The said blade 22 is secured on the saddle 23 by being placed in the groove *d* therein and then turning the screw *e* to drive 115 the wedge *b* between the border of said groove and the edge of the blade. It is obvious that the blade can be adjusted at pleasure in said saddle to bring the end of the blade which rests against the calender-roll to different distances from the contact-point of the two rolls. The said saddle 23 is adapted to rest on a round rod, as shown and described, in order 120 that the blade which it supports may, by the action of the said weight 25 thereon, have a 125 free vibratory movement on said rod, whereby one end is held with the requisite force against the roll which is required to guide the edges of sheets of paper downward as said sheets emerge from between the rolls, the said rod constituting the fulcrum on which the blade vibrates.

In practice several of the blades 22, with their saddles, are placed on each of the rods

16, opposite the calender-rolls. The rods upon which said saddles and blades are supported are adjustable vertically by means of the aforesaid slots in the arms 19, and also owing 5 to the fact that the bolts 7, which secure said arms to the strips 6, are adjustable vertically in said strips.

The saddle 24, as illustrated in Fig. 2, presents a similar but yet a different construction 10 to the saddle 23, which is above described, as the saddle 24, by its peculiar construction, and the manner of its attachment to its supporting-bar 26 does not permit of the movement of the blade 22, (see Fig. 1,) which is 15 attached thereto, excepting by means of an adjusting-screw, whereby it is retained in a particular position, and the manner of attaching said saddle to said bar by a shoe, 27, precludes the possibility of any rocking movement 20 of the saddle and its blade on said bar. The said bar 26, of metal or wood, is supported in the ends of two arms 13, one of which is shown in Fig. 1, which are secured on the inner sides of the aforesaid tape-roller 25 supports 9. The said shoe 27 is adapted to fit onto the upper side of the bar 26 and rest thereon, and said shoe and the saddle 24 are provided with hinge-lips, as shown, through which pivots pass, whereby the saddle is 30 hinged on the upper side of the shoe.

The shoe 27 has a laterally-projecting arm, 28, through the end of which a screw, 29, passes in a vertical direction against the under side of an arm, 30, which projects from 35 the end of the saddle. The end of the arm 30 is shown with a socket on it to receive the end of the screw 29; but said arm may be made with or without said socket. The saddle 24 is provided with said groove *o* on its 40 upper side to receive the blade 22, and with the wedge *b* and screw *e* shown and described in Fig. 4, and serving the same purpose as those in the last-named figure. The bar 26 serves to hold several of the saddles 24 and 45 their blades in the position relative to the upper side of the lower calender-roll shown in Fig. 1, the holding devices of said bar being so adjustable on the support 9 to swing the ends of the blades 22 in contact with said roll, and 50 after having been brought to that position the ends of the blades which rest on the rolls are forced against the latter with the requisite degree of pressure to secure a perfect separation of the sheets from said lower roll as they 55 come from the calender by operating the screw 29 against the end of the arm 30 and swinging the saddle 24 more or less.

Figs. 9 and 11 illustrate my improvements for guarding against the introduction by the 60 operator of more than one sheet of paper at a time between the rolls of the calender. These are provided in order that damage to the calender by feeding accidentally several sheets to it when the rolls are set for one only may 65 be obviated. Said sheet-guarding devices consist of several curved pivoted levers, 32, hung to vibrate freely on a bar, 33, which is sup-

ported over the upper roll of the calender by suitable standards, 34, resting on one of the journal-boxes, as shown. Each of said levers 70 32 has a roller or small pulley, 35, hung to one end thereof, and on the opposite end of said lever is formed a hook, 36. The end of said lever to which said roller is pivoted is the heavier one, and consequently the roller 75 constantly rides on the upper calender-roll, and the lever is so adjusted over the latter that at the same time the side of the said hook 36 is lifted away from the surface of the roll far enough to permit one sheet of paper to pass between it and the roll when only one sheet is fed to the calender under roller 35 from the table 37; but should two or more sheets of paper be inadvertently introduced between the roller 35 and the calender-roll the lever 32 is 80 thereby so swung on bar 33 as to carry the hook 36 thereon near enough to the side of the calender-roll to cause all of said sheets, excepting the under one, to be caught by said hook, and their passage through the calender is thereby prevented. The said standards 34, in which the bar 33 is supported, may be adjusted vertically by any suitable means in order to bring the hooked end of the lever 32 into proper relation to the adjoining surface of the calender-roll. In practice two or three of the levers 32 are hung above the calender-roll.

The features of the construction of the machine which are not claimed are shown and 100 described merely for the purpose of conveying a better understanding of the invention.

What I claim as my invention is—

1. In a paper-calendering machine, the strips 6, secured to the frame thereof, each 105 having a longitudinal groove therein of **T** shape in cross-section, combined with bolts engaging in said grooves, a spring located between the head of each of said bolts and the adjoining sides of said strips, a rod, 16, extending horizontally between said strips, and two rod-supporting arms, 19, secured by said bolts to said strips, substantially as set forth.

2. The roller-arm 19, slotted longitudinally and having a transverse clamp-screw near the 110 bearing therein, combined with a sleeve, 20, capable of a free movement in said arm, and a shaft having one end entering the end of said sleeve to a limited extent, substantially as set forth.

3. A blade-saddle for paper-calendering machines, consisting of the block having a groove to receive a blade, a tapering key entering said groove, and a screw entering said block and engaging with said key, combined 115 with a sheet-guiding blade, substantially as set forth.

4. Sheet-guiding devices for paper-calendering machines, consisting of a saddle, 24, provided with a groove to receive a blade, a 120 tapering key entering said slot, and a screw entering said saddle and engaging with said key, whereby the latter is given an endwise movement, and an arm, 30, projecting from

said saddle, combined with a shoe, 27, to which said saddle is hinged, having an arm, 28, thereon, and a screw therein engaging with said arm 30, a blade 22, and a supporting-bar for said shoe, substantially as set forth.

5. Sheet-guard devices for paper-calenders, consisting of several curved levers, 32, pivoted to vibrate over one of the rolls thereof,

said levers having a roller on one end which engages with the side of the roll and a hook on the opposite end capable of engaging with a sheet of paper on said roll, substantially as set forth.

CHARLES E. TORRANCE.
